UNITED STATES PATENT OFFICE.

SAMUEL BAXTERN WEBB, OF PERSONVILLE, TEXAS.

DESIGN FOR A KITCHEN-CABINET.

SPECIFICATION forming part of Design No. 26,371, dated December 1, 1896.

Application filed October 28, 1896. Serial No. 610,370. Term of patent 7 years.

To all whom it may concern:

Be it known that I, SAMUEL BAXTERN WEBB, a citizen of the United States, residing at Personville, in the county of Limestone and State of Texas, have invented and produced a certain new and original Design 5 for Kitchen-Cabinets; and I do declare the following to be a full, clear, and exact description of the invention, such as will enable others skilled in the art to which it 10 pertains to make and use the same.

My invention relates to a design for a kitchen-cabinet.

It relates to the entire configuration of the 15 cabinet, and especially to a cabinet constructed of wood.

My invention relates particularly to a cabinet as illustrated in the accompanying drawing, in which the figure represents a perspective view of a cabinet embodying my design.

The leading features of my design appear 20 in the following description:

1 represents the lower portion of the cabinet, having a forwardly, downwardly, and inwardly inclined front 2, around the face of 25 which is an ornamental projecting molding 3.

4 represents a ledge or shelf above the inclined front, and above this shelf is the plane horizontal top 5.

The whole cabinet is suitably ornamented 30 by molding, as shown in the drawing.

Having thus fully described my design, what I claim as new, and desire to secure by Letters Patent, is—

The design for a kitchen-cabinet, substantially as herein shown and described.

In testimony whereof I hereunto affix my signature in presence of two witnesses.

SAMUEL BAXTERN WEBB.
